US0D1010677S

(12) **United States Design Patent** (10) **Patent No.:** **US D1,010,677 S**
(45) **Date of Patent:** **** Jan. 9, 2024**

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventors: **Erica L. Clymer**, Northampton, PA (US); **Brian Michael Courtney**, Bethlehem, PA (US); **Sanjeev Kumar**, Harleysville, PA (US); **Sandeep Mudabail Raghuram**, Emmaus, PA (US); **Richard M. Walsh, III**, Bethlehem, PA (US); **Jennifer Wong**, Breinigsville, PA (US)

(73) Assignee: **Lutron Technology Company LLC**,
Coopersburg, PA (US)

(**) Term: **15 Years**

(21) Appl. No.: **29/855,727**

(22) Filed: **Oct. 6, 2022**

Related U.S. Application Data

(63) Continuation of application No. 29/822,507, filed on Jan. 10, 2022, now Pat. No. Des. 968,466, which is a continuation of application No. 29/774,948, filed on Mar. 19, 2021, now Pat. No. Des. 941,879, which is a continuation of application No. 29/649,798, filed on Jun. 1, 2018, now Pat. No. Des. 914,057, which is a continuation of application No. 29/562,240, filed on Apr. 24, 2016, now Pat. No. Des. 822,034.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with graphical user interface showing our new design.

The peripheral dashed broken lines illustrate a display screen or portion thereof, which forms no part of the claimed design. The interior broken lines illustrate portions of the graphical user interface which form no part of the claimed design.

1 Claim, 1 Drawing Sheet
(1 of 1 Drawing Sheet(s) Filed in Color)
